UNITED STATES PATENT OFFICE.

ROBERT FREDRICK TIMMONS, OF COSHOCTON, OHIO.

SIGN.

SPECIFICATION forming part of Letters Patent No. 578,613, dated March 9, 1897.

Application filed June 1, 1896. Serial No. 593,875. (No model.)

To all whom it may concern:

Be it known that I, ROBERT FREDRICK TIMMONS, of Coshocton, in the county of Coshocton and State of Ohio, have invented an Im-
5 proved Sign, of which the following is a speci-
fication.

The present invention relates to signs; and the object thereof is to provide a sign-board in conjunction with a supporting-frame
10 work which can be readily secured in any desired position, the sign-board being attached to a series of iron braces and wooden supports.

With this object in view the present in-
15 vention consists of the details of construction and arrangement which will more fully appear hereinafter.

In the accompanying drawings, which form a part of this application, Figure 1 is a rear
20 plan view of the sign-board attached to the supports and braces. Fig. 2 is a top plan view.

Like letters of reference indicate corre-
25 sponding parts in both views.

Referring to the drawings, A represents the sign-board, which may be of any shape, material, or size.

B represent rectangular-shaped uprights, having the curved braces b b secured to the
30 front edge e of the said rectangular-shaped uprights B B, the said uprights in the present instance being constructed of wood, as that

material is more convenient for my purpose. The said braces b b are so curved as to conform with the concave surface of the sign- 35 board A.

Zigzag iron braces d d are attached to the rear edges of the wooden uprights B B, their object being to strengthen and to hold them into position, thus making the sign-frame 40 rigid and stiff.

The object of making the supports of wood is to accelerate the fastening of the sign- board frame to the place in which it is de-
45 sired to be placed.

Having thus described my invention, what I claim as new, and desire to secure by Letters Patent, is—

In the herein-described sign, a framework, said framework consisting of rectangular 50 wooden uprights, curved braces secured to the top and bottom of the front edges of the said uprights, zigzag braces secured to the top and bottom of the rear edges of the said framework, a curved sign-board secured to 55 the said framework, substantially as set forth and described.

In testimony whereof I affix my signature in the presence of two witnesses.

ROBERT FREDRICK TIMMONS.
